UNITED STATES PATENT OFFICE.

OSCAR L. JOHNSON, OF STREATOR, ILLINOIS.

BRACKET.

980,532.

Specification of Letters Patent.

Patented Jan. 3, 1911.

Application filed May 18, 1910. Serial No. 562,085.

To all whom it may concern:

Be it known that I, OSCAR L. JOHNSON, citizen of the United States, residing at Streator, in the county of LaSalle and State 5 of Illinois, have invented new and useful Improvements in Brackets, of which the following is a specification.

My present invention pertains to brackets such as are designed to be fastened to buildings for the support of staging; and it has 10 for its object to provide brackets equipped with a simple and reliable safety attachment, adapted when the brackets are not in use to be expeditiously and easily detached 15 from the horizontal members thereof so that the complete apparatus can be stored in a small space.

With the foregoing in mind, the invention 20 will be fully understood from the following description and claims when the same are read in connection with the drawings, accompanying and forming part of this specification, in which:

Figure 1 is a perspective view illustrating 25 two brackets equipped with my novel safety attachment. Fig. 2 is an elevation of one end of the same. Fig. 3 is an enlarged plan of the outer portion of the horizontal member of one bracket. Fig. 4 is an enlarged 30 vertical section of the lower portion of one of the standards comprised in the safety attachment. Fig. 5 is a view taken at a right angle to Fig. 4.

Similar letters designate corresponding 35 parts in all of the views of the drawings, referring to which:

A A are the brackets, and B is the safety attachment, as a whole. The brackets A are 40 preferably, though not necessarily, foldable brackets of the general construction disclosed in my contemporary application filed Jan. 29, 1910, Serial Number 540,887, and it is therefore deemed unnecessary to specifically describe the same except to say that in 45 accordance with my present invention the horizontal channel-bar member *a* of each bracket is provided in the top of its outer portion with a plain slot *b* and a keyhole-slot *c*.

50 The safety attachment B comprises a rail *d*, preferably of wood, and end standards *e* which, like the brackets A, are preferably of metal. Each of the said end standards *e* is made up of a channel-bar upright *f* 55 equipped with a holder *g* in which the rail *d* is secured by a nail *h* or other means, and

a channel-bar horizontal-member or foot *i*, riveted at *j* to the inner sides of the side walls of the upright *f* and having a depending transversely-disposed oblong button *k* and a reduced circular portion *l* above the same, and also having a button *m*, of a shape and size to pass vertically through the large portion of the keyhole slot *c*, and a reduced portion *n* above said button *m*.

60 In assembling the parts of my improvements, the brackets A are disposed at right angles to the feet *i* of the safety-attachment B and are adjusted to enable the oblong buttons *k* to pass through the bracket slots 70 *b*. The brackets are then swung into alignment with the feet *i* to secure the buttons *k* at the undersides of the top walls *a*, and to enable the buttons *m* to pass downward through the large portions of the keyhole 75 slots *c*. The safety attachment is then moved outward on the brackets to carry the buttons *m* below the reduced portions of the keyhole slots *c*, whereupon, as will be readily understood, the safety attachment will 80 be safely and rigidly attached to the brackets.

To disconnect the safety attachment 85 from the brackets, the operation described is reversed, and then the brackets and the safety attachment can be shipped or stored in a small space.

While I have shown and described one form of my invention, it is to be understood that I am not limited to the details or the 90 form or relative arrangement of parts disclosed, but that modifications may be made therein without departing from the spirit thereof.

Having described my invention, what I 95 claim and desire to secure by Letters-Patent, is:

1. The combination with brackets having horizontal channel-bar members and also having a slot and a keyhole-slot in the top 100 wall of each of said members, of a safety attachment comprising a rail, and standards carrying said rail and each made up of a channel-bar upright, and a channel-bar foot fixed to and extending at an angle from the 105 upright and having at its underside an oblong button and a button of a shape and size to pass through the large portion of the keyhole slot.

2. The combination of brackets having 110 horizontal members, and a safety attachment comprising a rail and standards car-

rying said rail and having horizontal members superposed on the horizontal members of the brackets; one of each pair of the said superposed members being provided with a slot and a keyhole slot, and the other being provided with an oblong button and a button of a shape and size to pass through the large portion of the keyhole slot.

3. The combination of a bracket having a horizontal member, and a safety attachment having a horizontal member superposed on the horizontal member of the bracket; one of the superposed members be-

ing provided with a slot and a keyhole slot, and the other being provided with an oblong button and a button of a shape and size to pass through the large portion of the keyhole slot. 15

In testimony whereof I have hereunto set my hand in presence of two subscribing witnesses. 20

OSCAR L. JOHNSON.
